UNITED STATES PATENT OFFICE.

FRANKLIN LASHER, DECEASED, LATE OF UTICA, NEW YORK, BY RUSSEL LASHER,
ADMINISTRATOR, OF BRISTOL, CONNECTICUT, ASSIGNOR TO UTICA KNITTING COM-
PANY, OF NEW YORK, N. Y., A CORPORATION OF NEW YORK.

KNITTING-MACHINE.

1,199,995.

Specification of Letters Patent.

Patented Oct. 3, 1916.

Application filed June 27, 1913. Serial No. 776,181.

To all whom it may concern:

Be it known that FRANLIN LASHER, deceased, a citizen of the United States, and late of the city of Utica, county of Oneida, 5 State of New York, has invented new and useful Improvements in Knitting-Machines, of which the following is a specification.

The invention relates to circular rib knitting machines particularly adapted for 10 spring needles and consists in means for supporting, adjusting and operating the cylinders, particularly in means for separating the cylinders more conveniently to put on the cloth at the beginning of operations and means for throwing certain parts 15 out of operation while the cloth is being put on and the machine started.

The important features of the invention are a single central standard carrying a solid, 20 main table on which are supported the cylinders, the driving means and all parts whereby the usual operation of the machine is effected. All said parts are arranged above this table except the main drive-shaft, the 25 bracket therefor and the adjacent parts. From this table rise two posts, one having lateral extensions at its upper end, affording a firm three-point support for the upper table which carries the upper cylinder, its 30 gear, needle cams, etc.

The lower or main table is provided with a comparatively small central bearing for the hub of the lower cylinder gear, so that the supporting standard and lower table may 35 be designed and made of standard size for machines having different size cylinders.

As a new feature, means are provided for separating the cylinders a substantial space for convenience in initially starting the operation of knitting the tube of fabric, which 40 consists in applying a piece of old fabric to one set of needles, threading up the various parts, commencing operations and arranging the various parts so that they will co-operate and continue knitting when the power 45 is applied, commonly called "putting on the cloth." This separation of the cylinder edges a substantial space, in which the workman can conveniently operate, is preferably 50 effected by raising the upper table and this

is done by means of a crank operated screw-rod in the standard, an arm, or "yoke" on said screw-rod and vertical rods on the arm guided in the posts to engage with the upper table. While this is being done it is desirable to maintain the pressers, thread guides and sinkers out of position, and thereafter, temporarily to maintain, the secondary set of needles out of operation until the old cloth has run off the first needles and the machine is in shape to operate smoothly. He has devised desirable means whereby said parts may be maintained out of operative position and returned thereto. With the aforesaid parts he has combined means for 55 convenient and accurate adjustment of the upper cylinder with reference to the lower; vertically, to vary the distance between the cylinder edges for varying the stitch or to provide for a different weight of yarn;—60 circumferentially, to insure chiming of the needles. By the special form and arrangement of the new machine, the operating shafts, gears, etc., are firmly supported 65 against all strains.

In the drawings Figure 1 is a rear elevation of the machine, showing the cylinders in separated position, and with a portion of the standard in section to show the crank and screw-rod whereby the upper table and 70 cylinder are raised. Fig. 2 is an elevation, with parts in section, of the upper portion of the machine at a right-angle to the preceding, showing the cylinders in close or operative position. Fig. 3 is an enlarged 75 vertical section parallel to Fig. 2. Fig. 4 is an enlarged vertical section of the cylinder edges and adjacent parts to illustrate the means by which the pressers, thread guides, lower needles, etc., are thrown out of normal 80 position while the cloth is being put on. Fig. 5 is a plan of Fig. 4 taken just above the cam bed and the depending pressers. Fig. 6 is an elevation of the presser bracket and sleeve. Fig. 7 is a vertical section of the 85 thread guide. Figs. 8 and 9 are respectively a vertical cross section and a front elevation of the lower needle cam. Fig. 10 is a vertical section of the upper table edge and one 90 of the posts fitted thereto showing means by 95 100 of the posts fitted thereto showing means by

which the upper cylinder is adjusted vertically with reference to the lower. Fig. 11 is an elevation of the graduated post cap and washer shown in the preceding. Fig. 12 is a plan showing the upper table supported at three points and the spur gear. Fig. 13 is a partial plan and partial section of said spur gear to show the means for adjusting the upper cylinder circumferentially with reference to the lower.

Frame and supporting parts for the tables, (Figs. 1, 2, 3.)—1 indicates the single, central standard having the enlarged base 5 to stand securely on the floor of the mill and 2 the standard top secured in position by cap-screws 3. The standard top is enlarged above firmly to carry the lower table A, thus constituting a rigid supporting frame for the other parts, all of which are arranged above said table except the drive-shaft bracket 4 and the parts immediately adjacent thereto. The standard is preferably a hollow casting circular in cross section. In the center of the table A is the bearing 6 having a comparatively small opening in which is fitted the hub of the lower cylinder gear, or lower gear, C; having teeth 7 on its periphery and a hub 8 fitting said opening and fitted around the cam sleeve D. To this lower gear is secured by cap-screws 9 the lower cylinder casting E on which is shrunk the lower cylinder F, slotted for the lower needles 11 and jacks 12, held in position by elastic encircling bands 13. H is the matrix ring shrunk on to the lower cylinder and having its upper edge notched at 15 (Fig. 4) to receive the primary needles while the yarn is being fed into them by the sinkers 16 carried by the sinker-bed J, which is consolidated with the lower cylinder and matrix ring so as to revolve therewith. These sinkers are actuated by the slur-cock 18 carried in the sinker-bed cap 19 rigidly supported on posts L and K. Said post L and the extensions K' of post K afford a firm, three-point support for the upper table B formed with the bearing 20 to which is fitted the upper cylinder gear M. To this is secured by screws 21 the upper cylinder casting N on which is shrunk the upper cylinder G provided with needles 22, jacks 23 and circular bands 13 corresponding to similar parts fitted to the lower cylinder. He has omitted on the right but shown on the left the cam brackets and cams for operating the needles. 25 is the lower cam and 26 the lower cam bracket supported on table A; 27 are the upper cams and 28 the upper cam brackets bolted to the under surface of upper table B.

Means for adjusting the upper cylinder, (Figs. 2, 3, 10, 11.)—Where a different yarn is to be used or a slight change made in the stitch, it is necessary slightly to raise or lower the upper cylinder with reference to

the lower. Heretofore means have been suggested for adjusting the upper cylinder such as slotted supports and adjusting screws engaging with parts connected to the upper cylinder, but such means required an experienced mechanic and careful manipulation, aided by a gage at each change in adjustment, and there was always danger of getting the parts slightly out of level and out of concentricity.

He has devised means by which the upper table carrying the upper cylinder is adjusted initially with absolute accuracy with reference to the lower and thereafter changes in adjustment may easily be made by the ordinary operator without any danger of getting the parts out of true.

The weight of the upper table B is supported on the hollow posts K and L but is raised to separate the upper cylinder from the lower initially in putting on the cloth by means of the raising rods x x' extending from the raising member y upwardly to the upper table. The front rod x extends through post L, the two rear rods x' extend on each side of the rear post K through the extensions K'. To the upper end of each of said rods is fitted the guiding stud 29 having the thread 30 for the graduated post cap 32 which rests on the upper end of the post. The stud is provided with shoulder 34 on which rests the hollow washer 35. By means of nut 36 and washer 38 the table is clamped securely on the hollow washer and thus to the stud. This is best shown in Fig. 10. Initially the tables and cylinders are adjusted with great care to be absolutely true, that is concentric and parallel, and when this has been done the point 40 is marked on washer 35 to correspond to the zero on cap 32, the cap being clamped fast by set-screw 41, having a soft leather plug 41' between the screw and the thread to protect the latter. See Fig. 10.

When it is desired to raise the upper cylinder, that is to readjust it with reference to the lower, it is only necessary to loosen the set-screws of the post-caps 32 and shift the latter each a certain number of scale spaces (marked on the post-caps) with reference to the point 40 on the washer 35. See Fig. 11. The post-cap rests on the upper end of the post and therefore, when the former is turned, it is evident that it will raise the table and separate the cylinder edges; this is easily done by the workman of ordinary skill without possibility of disturbing the parallelism or concentricity of the cylinders, for all that is necessary is to turn each post-cap the same number of spaces of the scale, and the correctness of such adjustment is easily observed by the foreman. For rotating the post-cap, wrench holes are provided therein as shown in Fig. 11. The lifting rod is not secured at its lower end to the yoke y,

so that it may be slightly raised therefrom as the post-cap is turned. It will be understood that initially the cylinders are adjusted with minimum space between them so that 5 the upper is raised for separation, and may be lowered by turning the post-caps in the reverse direction to again bring the cylinders together. A very delicate adjustment is possible, for instance the thread 30 may be made 10 to the inch and a scale of 100 inscribed on the post-cap, which permits an adjustment to the one-thousandth of an inch.

He has shown in Fig. 10 a desirable means 15 for fitting the studs to the rod. The upper end of the rod α is formed with a beveled shoulder 45 and a threaded tip 46 and the lower end of the stud correspondingly formed with a bevel and a threaded socket, so that, when screwed together, correct 20 alignment is insured. It would be simpler to form the stud and the lifting rod in one piece, that is continuous, but then it would be very inconvenient to take the machine apart, so a connection is formed between 25 them by means of the thread 46, to permit the rod to be backed off from the stud by the wrench from below. When you tighten up this connection the bevel insures accurate centering.

30 The above described construction of adjusting parts is preferably to the slight modification thereof shown at the upper left hand corner of Fig. 3, where the stud and the lifting rod have a butt-end joint at c 35 with a tip on one part fitting a socket on the other. If the parts are not absolutely true or if there is any looseness there is danger of binding. By the above described arrangement of guiding studs the parts are at 40 all times secured against lateral displacement so that the concentricity of the cylinders is maintained in all adjusted positions.

Means for raising the upper table when the cloth is being put on, (Figs. 1, 2, 3.)— 45 On the side of the standard top 2 there is provided a horizontal bearing 48 for crank-shaft 49 having angular shank 50 on outer end for the crank and a miter gear 52 on its inner end meshing with interiorly threaded 50 miter gear 53, which rests on the tubular portion 55 in the interior of standard 2 provided to receive the threaded lifting rod 56, gear 53 being internally threaded to mesh 55 with the thread on rod 56. This lifting rod extends downwardly in said tubular portion and carries rigidly fixed to its upper end the yoke γ . At its front end this yoke carries one of the three raising rods α and on the cross-arm 58 at its rear end the other two 60 rods α' , which rods are fitted at their upper ends to the studs 29, whereby the upper table may be easily raised into the position shown in Fig. 1 to afford a manipulating space between the cylinder edges. A space 65 of two to three inches or more is afforded

between the cylinders making it more convenient, particularly for the ordinary operator to put on the cloth, so that much time is saved. But to do this successfully, it is better to throw the lower needles out of operation until the old cloth has been run off the upper needles, thus avoiding the crowding of the cloth on the two sets of needles with danger of bending and breaking them.

The upper end of post L, also the bearing 70 ends of the arms K', are desirably split as best shown in Figs. 1 and 10 and provided with ears 59 for the clamping bolts 60 whereby the upper table is clamped down rigidly in operative position. The adjusting and supporting parts are adapted to permit of the cylinders being separated for putting on the cloth without in the least disturbing the adjustment of the cylinders when they are returned to operating position.

Means for shifting parts out of operative position while putting on the cloth, (Figs. 4 to 9.)— During the above described separation of the cylinders and while starting the 90 machine, he has found it convenient to shift out of operative position certain parts such as the pressers, sinkers, thread-guides and lower needles, and has devised, means for conveniently so shifting such parts and then 95 returning them to operative position.

The parts and the means for shifting are as follows: 26 is the lower cam bracket secured by its base on the lower table A and carrying the lower cam 25 hinged or pivotally connected to the bracket at 61. The upwardly extending arm of the bracket is provided with an opening to receive the sleeve 62 carrying the plunger 64 having the handle 65 on its outer end and forced inwardly by the spring 66 to engage with a notch or hole 68 in the cam, holding the latter up into operative position (Figs. 8 and 9). When the plunger is pulled out against the force of the spring the cam falls (as shown in dotted lines in Fig. 9) so that the needles as they reach this point are not raised but remain out of action and away from the work. To restore the cam to operative position it is merely necessary to raise 115 it by hand until the plunger engages with hole 68.

The upper cam brackets 28 carrying the upper cams 27 for the upper needles, are bolted to the under surface of the upper table B. On these brackets are secured the upper and lower presser brackets 70 and 70' provided with horizontally extending bearing studs 72 to which are fitted sleeves 73 carrying the presser shanks 74 and the pressers P P'. In the end of each bracket is arranged a small plunger 76 adapted to engage with a hole 78 in the sleeve to maintain the presser out of operative position when the cloth is being put on the machine and 130

started. See Figs. 4 and 6. The non-operative position is shown in dotted lines in Fig. 4. Evidently the plunger could be arranged in the sleeve and the holes made in the 5 studs. In Figs. 4, 5 and 7 are also shown the matrix sinker supporting and operating mechanism and the arrangement of thread guides, permitting the latter also to be 10 swung out of position during the said operation of starting the machine.

As aforesaid H is the matrix ring, 16 are the sinkers carried in the sinker bed J, and 19 is the sinker-bed cap, 18 and 18' are the slur-cock cams, 80 is a stud clamped to cam 15 18' by nut 81, and 83 is a set-screw in said stud engaging with clip 84 on sinker-bed cap 19, whereby the position of the cam may be adjusted and the length of the stitch be varied. 86 is an eccentric lever journaled 20 on said stud whereby the slur-cock may be withdrawn from working position carrying the sinkers outwardly away from the primary needles so as to provide a space for the convenient threading of the needles. 25 88 is the thread-guide tube carried on the inner end of arm 89, whose outer end has an upturned lip f provided with one or more holes for the thread and is slotted at g, affording a slight adjustability on the screw 30 h, whereby the arm is secured to the pin, or plunger, 91, held down in position by spring 92 in socket 90, having arm j whereby it is fixed on the sinker-bed cap. To shift the thread guide out of operative position 35 shown in Figs. 4 and 5, pull up the arm against the force of the spring to release from notch 94, or other locking means, said notch 94 being formed in the socket 90, and the plunger 91 being provided with a pin or 40 projection to engage with said notch and lock the guide in position, and give the guide a quarter turn to swing it away from the needles, in which position the thread-guide will rest on the cap, and be in a convenient position for threading. When in 45 working position, it is difficult to thread the tube 88.

By considering the operation of putting on the cloth, the convenience of the above 50 described means will be evident. The steps of that operation are as follows: First, turn up all the pressers to be maintained by their locking plungers 76 away from the needles. Lift the thread guide by its sleeve and swing 55 it around out of operative position. Withdraw the slur-cock by the lever 86. Pull out the plunger 64 to drop the lower cam. Raise the upper table by means of the crank 60 and lifting mechanism to carry the upper cylinder away from the lower. Hold the edge of the cloth up against the upper needles and turn the cylinder till they all hook through the cloth. Then lower the upper cylinder, turn the thread guide into operative 65 position, throw in the slur-cock, and

then lower the pressers of the upper set. Then start the machine and run it till the old cloth is run off and the upper needles are knitting the new thread, then drop the pressers of the lower set and raise the lower cam into operative position, and continue knitting.

Power transmitting parts, (Figs. 2 and 3.)—Beneath the rear extension A' of the lower table A is bolted the driving shaft 75 bracket 4, whose weight is also supported on the auxiliary standard 97. In this bracket is journaled the main drive shaft S carrying on its outer end the power pulley R adapted to be coupled to the shaft by any 80 suitable clutch mechanism for instance an expanding ring r within the pulley and merely conventionally shown as it is a well known means. Said ring may be expanded to engage with the inner surface of the 85 pulley, and lock the latter to the ring, by means of a suitable wedge on sliding collar 100, fitted to slide freely on the main drive shaft, and having a groove for engagement of any suitable lever to be operated by hand 90 for starting and stopping the machine. Said collar also engages with any suitable stop-motion device, commonly employed.

For hand turning there is provided the hand-wheel shaft 104 provided with a hand-wheel, not shown, and a worm 105, meshing with worm gear 106 arranged to turn the main drive shaft by a ratchet connection between it and ratchet ring 108 affixed to said shaft. This ratchet connection is of 100 usual construction and therefore not necessary to be shown, and is provided so that the shaft etc. may be turned by the hand-wheel, but the hand-wheel is not turned, but stands idle, when the parts are operated by 105 power, thus eliminating objectionable momentum and enabling stop motion to work, more quickly.

On the main drive-shaft S at any suitable point adjacent its inner or front end as here 110 shown is secured the miter gear 110, in engagement with miter gear 112, secured by suitable pin 114 to the vertical drive-shaft T which is journaled in rear post K. This post has a tubular extension K' extending 115 down through an opening 115 in the table, and the miter gear 112 having spur gear 116 on its upper periphery in mesh with teeth 7 of lower gear C, is made of this peculiar dished construction, so that the bearing for 120 the vertical shaft may be extended down to the lowest point to afford a firm support against the lateral thrust. Near the upper end of the vertical drive shaft T is the small shoulder T' resting on the upper end of 125 post K and the large shoulder T², on which is carried the upper or elongated spur gear U in mesh with the upper gear M and having the hub U' fitting the upper end of the vertical shaft.

Chiming the needles. (Figs. 3 and 13.)—Means are provided to effect a slight circumferential adjustment of this upper spur gear U with reference to the vertical shaft T and the lower spur gear 112 whereby the upper cylinder may be adjusted with reference to the lower and the needles be made to chime; that is the upper needles be set exactly in the center of the spaces between the needles of the lower set. This means consists of a pin 118 depending from elongated gear U into a slightly larger hole 119 in the shoulder T². Into this hole extend the two set-screws 120 to engage with the pin whereby the elongated gear is adjusted to its shaft. By loosening one set-screw and tightening the other a slight circumferential shift may be given to the elongated gear and this correspondingly shifts the upper cylinder to bring the two sets of needles into proper relation as aforesaid. When this adjustment has been made the cap 122 is clamped down by bolt 123 thus performing the functions both of a cap and of a clamp rigidly to clamp the gear in its adjusted position.

Other parts.—The cam-sleeve D is shown supported by an integral bearing flange 126 having a supporting bearing on the hub 8 of lower cylinder gear C, with the bearing washer 128 interposed between the bearing surfaces. The sleeve D is held stationary by suitable holding arms 130 and has clamped on its upper portion the cam supporting ring 131. On the ring are arranged segments 132 as here shown at one side only, carrying cams 134 suitably to coat with the needles to effect the proper knitting operation. The particular function of the cams of course is to force out the lower needles so that the previously formed loops may be cast off. An adjusting screw 136 is arranged in the hub 138 of the cam supporting ring 131 to adjust the ring and cams vertically and said hub is split and provided with clamping ears for the clamping bolt 140 by which it is secured; after the parts are adjusted to accommodate them to the adjustment of the cylinders.

A vertical take up drive shaft 142 is arranged in the inner vertical bearing of the sleeve D and has keyed on its lower end the transmission plate 143 carrying a pin 144 connecting it to rotate with the lower gear C by being fitted to an aperture in said gear. A take up shaft 146 extending upwardly to the usual take up mechanism, is rotatively connected to its drive shaft 142 by means of a suitable knuckle joint connection and a supporting or bearing collar 147 keyed to the upper end of shaft 142 and resting on the upper end of sleeve D whereby the take up driving parts are supported. Suitable provision is made to permit the connecting pin 144, through which the motion is communicated to the take up, to pass the hold-

ing arms 130 in its rotation but the means employed are not necessary to be here shown.

On the upper surface of table B is screwed the guard plate 150 to cover gear M, and at 151 is shown a guard extension integral with the table to surround the gear U whereby protection from injury by said gearing is afforded.

To avoid the dripping of oil through the hollow standard on to the floor he has, as an improvement, modified the parts as shown in Fig. 1, the standard 1, commonly made of cast metal, is formed with a solid partition k, and an opening m, through the wall of the standard, so that all the oil, dripping down from above, drips out through the opening and flows down outside into the base, formed with the channel n to receive it whence it may be wiped up from time to time; thus the oil is carried outside preventing an objectionable accumulation of oil where it would be inaccessible.

Conclusion.—The various mechanism here described, whereby the cylinders are supported, separated and accurately adjusted, and the manner in which they are combined to produce a strong and compact machine, greatly increase the convenience and certainty of operating the machine and contribute to the production of practically perfect work. Convenient access to all parts is permitted by the simple central standard, without projections, which is simple and economical to construct and to install. This standard and the lower table, carrying the front and rear posts form a strong, solid, compact frame to carry the operating parts; and said parts are thus carried on a three-point support, which is the best possible, for this gives a firm support without danger of springing as with a two point support, and without danger of warping as may occur with a four point support where one point is lower than the others. This supporting frame is also compact and permits easy access to all the operative parts for the rear post and its extensions are little wider than the spur-gear and both the front and rear posts are arranged at a sufficient distance from the cylinders to afford space for the cam brackets, sinker bed, sinker bed cap, etc. The adjusting and lifting mechanisms for the upper table and cylinder are so combined with said supporting parts as not to interfere with the compactness of the machine or accessibility to the parts.

While the various parts here described are particularly adapted to circular rib knitting machines having spring needles yet he does not propose to limit them to such machines, but desire to protect their use in any kind of machine in which they may be desirable.

Having described the invention he claims:

1. A circular knitting machine having

suitably disposed needle cylinders, supporting members for the cylinders, one of said members arranged to be adjustable relative to the other, guiding studs adjustably carried by one member in engagement with the other of said members to guide the adjustment of the cylinders, gage collars on one of the supporting members and rest collars adjustably supported on the studs to adjust 10 the relative operative positions of the cylinders, one of said collars having graduation marks thereon for adjustment with relation to the other.

2. In a circular rib knitting machine comprising upper and lower cylinders, upper and lower tables for supporting respectively the upper and lower cylinders, posts on the lower table to support the upper table, studs corresponding in number to the 15 posts and having threaded lower ends, integral shoulders on the studs, hollow washers fitted to said shoulders and engaging with the under surface of the upper table, means to clamp the table on the hollow 20 washers against the shoulders, post caps or rest collars fitted to the threaded lower ends of the studs and provided with means for the engagement of a wrench, and set-screws to fix the post caps on the studs, said hollow 25 washers and post-caps being suitably marked to indicate the relation of each washer and adjacent cap.

3. A circular rib knitting machine comprising a suitable supporting standard, a 30 lower table supported on the standard, a lower cylinder fixed on said table, posts on said table, an upper table supported on the posts, the upper cylinder supported on the upper table, a threaded tube vertically arranged in the standard, a threaded lifting 35 rod fitted to the tube, a horizontally arranged yoke on the upper end of the rod, vertical raising rods on the yoke connected at their upper ends to the upper table and 40 means to rotate the threaded vertical tube and thereby raise and depress the upper table and upper cylinder with reference to the lower table and cylinder.

4. A circular rib knitting machine comprising a suitable supporting standard, a 45 lower table supported on the standard, a lower cylinder fixed on said table, posts on said table, an upper table supported on the posts, the upper cylinder supported on the 50 upper table, a threaded tube vertically arranged in the standard, a threaded lifting rod fitted to the tube, a horizontally arranged yoke on the upper end of the rod, vertical raising rods on the yoke connected 55 at their upper ends to the upper table and supported freely on the yoke and means to rotate the threaded vertical tube and thereby raise and depress the upper table and upper cylinder with reference to the 60 lower table and cylinder.

5. A circular knitting machine having a supporting standard a lower cylinder supporting member on the standard, a lower needle cylinder rotatably supported thereon, supporting posts on the lower supporting 70 member, an upper cylinder supporting member, guide-studs depending therefrom and entering apertures in said posts, rest collars adjustable carried on said studs normally to support the upper cylinder, an 75 upper needle cylinder rotatably supported on the upper cylinder supporting member, a centrally arranged cam supporting sleeve suitably arranged to be supported on the lower supporting member, take-up connections, said lower supporting member affording a bearing for the take-up connections, gears carried by the cylinders, connections thereto whereby the gears and cylinders are rotated in unison, upper cylinder raising 80 mechanism having supporting rods entering the post apertures from beneath whereby the upper cylinder may be raised from its normal operating position without affecting the adjustment of the rest collars. 85

6. A circular knitting machine having a supporting standard, a lower cylinder supporting member on the standard, a lower needle cylinder supported thereon, oppositely arranged supporting posts on the 90 lower supporting member, one of said posts providing bearings for a drive shaft and having arms extending therefrom, an upper cylinder supporting member, adjustable rest parts carried by one of the supporting members to be supported by the posts, means to guide the supporting parts in their adjustment and an upper cylinder raising mechanism having supporting rods upwardly extending through one post and through the 100 arms of the other post whereby the upper cylinder may be raised from its normal operating position without affecting its normal support.

7. A circular rib knitting machine comprising lower and upper cylinders, a lower table carrying the lower cylinder, posts on the lower table, an upper table carrying the upper cylinder and sustained on said posts, studs for the upper table, means to clamp 115 said upper table on said studs, caps on said studs, said caps resting on said posts and being fitted to threads on the studs for rotation thereon and varying the relation of the upper table to the lower. 120

8. A circular rib knitting machine comprising lower and upper tables, lower and upper cylinders on the respective tables, posts on the lower table sustaining the upper, studs fitted to the upper table to correspond to the posts, means to clamp the upper table on the studs, caps engaging the posts and fitted to threads on the studs for rotation thereon to vary the relation of the upper cylinder to the lower, and indicators 130

on each cap to indicate the extent of such variation.

9. In a rib knitting machine a suitable standard, a lower table thereon, a lower cylinder supported on said table, posts on said table, an upper table resting on said posts, the upper cylinder secured on said upper table, a vertically movable part arranged below the standard, rods from said part extending upwardly through the lower table to the upper table, and means for raising said part, also the upper table carried on said rods, and the upper cylinder, substantially to separate the cylinder edges, affording a working space therebetween, and then to lower said part to restore the upper cylinder to normal position.

10. A circular rib knitting machine comprising lower and upper tables, lower and upper cylinders sustained on the respective tables, posts upwardly extending from the lower table to carry the upper studs fitted to the upper table in line with the posts, means to secure the upper table on the studs, caps threaded on the studs and engaging with the posts for varying the relation of the upper cylinder to the lower, a moving part arranged below the lower table, rods extending therefrom to the upper table and means to raise and lower said moving part substantially and temporarily to separate the cylinder edges and to restore them to initial position.

11. In a circular knitting machine having a pair of corresponding needle cylinders suitable supports therefor, means for adjusting one cylinder with relation to the other comprising a plurality of supporting members for said first cylinder, one part of each of said members being fixed with relation to said first cylinder and another part being rotatable with relation thereto to move the same with relation to the other cylinder, a scale on one of said parts and an initial mark on the other of said parts to indicate the exact extent of such movement and rotation.

12. In a circular knitting machine having a suitable standard, a lower cylinder supported thereon and an upper cylinder, means for adjusting the upper cylinder with reference to the lower, comprising a plurality of posts carried on the standard, a plurality of downward extensions connected to the upper cylinder and corresponding to the posts, and caps fitted to threads on said extensions and resting on the posts for supporting the upper cylinder.

13. In a circular knitting machine having upper and lower tables, upper and lower cylinders on the respective tables, and a suitable standard for supporting the lower table, means for adjusting the upper parts with reference to the lower comprising a series of posts on the lower table, a corresponding

series of downward extensions on the upper table, said extensions being suitably threaded and caps fitted to said threads and resting on the posts for carrying the weight of said upper table, the caps being rotatable on their threads for adjusting the elevation of the upper table, and said caps, or an adjacent part connected to the upper table, with reference to which the caps are rotated, being provided with graduation marks for indicating the extent of adjustment.

14. In a circular rib-knitting machine having upper and lower cylinders, upper and lower tables for the respective cylinders and a suitable standard for the parts, the lower table being carried on the standard and a plurality of posts on the lower table, means for adjusting the relation of the upper cylinder to the lower, comprising a plurality of studs corresponding to the posts, means for clamping the upper table on the studs, and caps fitted to threads on the studs and resting on the posts to carry the weight of the upper parts, said caps being rotatable on the studs to adjust the upper table up or down.

15. A rib knitting machine comprising a suitable standard, a lower table, a lower cylinder on the table, an upper table, an upper cylinder on the upper table, carrying means for the upper table extending downwardly below the lower, and means arranged below the lower table and connected to said carrying means temporarily to raise the upper table.

16. A rib knitting machine comprising a suitable standard, a lower table thereon, a lower cylinder on the lower table, an upper table, an upper cylinder on the upper table, rods downwardly extending from the upper table through the lower table and means engaging with said rods below the lower table to effect temporary elevation of the upper table and upper cylinder.

17. A rib knitting machine comprising a standard, upper and lower cylinders suitably supported on the standard, means to vary the operative relation of the cylinder edges to each other and means to indicate the extent of such variation, carrying means temporarily to carry the upper cylinder in a raised position, said carrying means extending downwardly below the lower cylinder, and raising means, arranged and engaging with the carrying means below the lower cylinder, temporarily to raise the upper cylinder for affording a working space between the cylinder edges and to return the upper cylinder to normal operative position without disturbing the said operative relation of the cylinder edges.

18. A rib knitting machine comprising a hollow standard, upper and lower cylinders suitably supported thereon, a yoke extending across said standard and arranged below the lower cylinder, temporarily operat-

ing carrying means connected to the upper cylinder and extending down to the yoke, and raising means arranged in the hollow standard and connected to the yoke temporarily to raise the yoke, the carrying means and the upper cylinder, affording a working space between the edges of the two cylinders.

In testimony whereof I have signed my

name to this specification in the presence of 10 two subscribing witnesses.

RUSSELL LASHER,

*Administrator of the Estate of Franklin
Lasher, deceased.*
